Primary Examiner—Theodore M. Shooman*Assistant Examiner*—Sandra Morris*Attorney, Agent, or Firm*—Hayes & Reinsmith**[57]****CLAIM**

The ornamental design for a lawn and garden blower apparatus, as shown and described.

DESCRIPTION

FIG. 1 is a perspective view of our design;
FIG. 2 is a left side elevational view of the design;
FIG. 3 is a right side elevational view of our invention;
FIG. 4 is a bottom view of our invention;
FIG. 5 is a top view of our invention;
FIG. 6 is a rear view of our invention; and,
FIG. 7 is a front view of our invention.

FIG. 1

FIG. 2

FIG. 3

FIG. 4

FIG. 5

FIG. 6

FIG. 7
